UNITED STATES PATENT OFFICE.

OSCAR BRÜNLER, OF LEIPZIG, GERMANY.

STEAM-GENERATOR.

SPECIFICATION forming part of Letters Patent No. 760,519, dated May 24, 1904.

Application filed September 10, 1903. Serial No. 172,572. (No model.)

To all whom it may concern:

Be it known that I, OSCAR BRÜNLER, mechanical engineer, a subject of the Emperor of Germany, residing at Leipzig, in the Kingdom 5 of Saxony, Germany, have invented certain new and useful Improvements in Steam-Generators, of which the following is a specification.

My invention relates to steam-boilers in 10 which the combustion of a gaseous mixture under pressure takes place directly in water; and it consists, essentially, in the arrangement that the boiler containing the water and the fuel is made very small and is in communication 15 with a greater boiler, which is not directly heated.

In order to better explain the object of the invention, it is shown in the two accompanying diagrams, of which—

20 Figure 1 is a diagram of the apparatus used in carrying out this invention, the larger boiler being shown in vertical section. Fig. 2 is a vertical section of the steam-generating boiler drawn to a larger scale.

25 The steam-generator consists of two receptacles A and B. The first contains the feed-water and the produced steam, and the second is the steam-generator. The two receptacles communicate by a pipe c, by a water-pipe d, 30 and by a steam-pipe e. In the pipe d is inserted a shut-off valve i and in the pipe e a shut-off valve k. The pipe c may be closed, if necessary, by a sliding valve. The steam-generator is made very small in order to place 35 therein only the burner and sufficient water for surrounding the flame of the burner to prevent it from coming in contact with the walls of the steam-generator. At the mouth of the burner f, placed in the steam-generator B, the flame t burns below the water-surface.

g is a heating-lamp having a cover h.

The combustibles and the combustion-air are forced into the burner under a pressure 45 which must be greater than that in the boiler. Pipe s, with a shut-off valve q, conducts the combustion-air into the burner. The pipe r, with a shut-off valve p, conducts the combustibles. The pipe o, leading to pipe s, and pipe 50 n, leading to the pipe r, conduct the com-

pressed air and the combustibles into the heating-lamp. Shut-off valves l and m are provided in the pipes o and n.

Having described the construction of my invention, I now describe its operation. At 55 first the shut-off valves i and k and the sliding valve c are closed to separate the boilers A and B. When the cover h of the heating-lamp g is opened, the steam cannot escape from the boiler A. After the heating-lamp g is heated 60 inside the shut-off valves l and m are opened and the combustibles are forced through the pipe n and the compressed air is forced through the pipe o into the heating-lamp g. The combustible mixture is ignited by any means and 65 the cover h is shut. The burning gaseous mixture makes its way through the burner f, and the products of combustion pass through the water, delivering heat to the water and collecting with the steam in the upper part of the 70 steam-generator. As soon as the pressure in the steam-generator is high enough the shut-off valve k, provided in the steam-pipe e, is opened. In a few minutes the small quantity 75 of water in the steam-generator B begins to boil, and then the shut-off valve i in the water-pipe d and the sliding valve c are opened. A and B being now in communication by all pipes, the valves p and q are also opened in order to conduct the combustibles through the 80 pipe r and the compressed air through the pipe s into the burner f, in which the combustible mixture is ignited by the projecting flame of the heating-lamp. The flame t shoots out of the mouth of the burner f, whereby the 85 water is set in very rapid motion, thereby preventing the boiler from incrusting. Since the boilers A and B are in communication by the sliding valve c, a strong current of hot water passes from B to A and cold water from A 90 to B.

What I claim as my invention is—

1. In a steam-generator the combination with a boiler, which is not directly heated of a steam-generating boiler, in which the combustion of a gaseous mixture under pressure takes place directly in water, as set forth. 95

2. In a steam-generator in combination with a boiler, which is not directly heated, a steam-generating boiler, being made very small in 100

which the combustion takes place directly in water, and pipes connecting both boilers, as specified.

3. In a steam-generator in combination with a boiler, which is not directly heated, a very small steam-generating boiler, in which the combustion takes place under water, pipes connecting the boilers and shut-off valves provided in the pipes, as set forth.
- 10 4. In a steam-generator in combination with a boiler, which is not directly heated, a very small steam-generating boiler, in which the

combustion takes place under water, communicating with the above boiler by a steam-pipe, by a water-pipe and by a pipe situated at the ¹⁵ water-level, shut-off valves provided in the pipes and a heating-lamp, which may be closed by a cover arranged on the burner of the small steam-generating boiler as set forth.

OSCAR BRÜNLER.
